MANUFACTURING COMPANY, A CORPORATION OF NEW JERSEY.

MECHANISM FOR CLIPPING HOLES IN SHEET MATERIAL.

1,347,486.

Specification of Letters Patent.

Patented July 27, 1920.

Application filed May 13, 1918. Serial No. 234,132.

To all whom it may concern:

Be it known that I, EDWARD B. ALLEN, a citizen of the United States, residing at Bridgeport, in the county of Fairfield and State of Connecticut, have invented certain new and useful Improvements in Mechanisms for Clipping Holes in Sheet Material, of which the following is a specification, reference being had therein to the accompanying drawings.

This invention relates to coacting punch and anvil devices for clipping holes in sheet material. More particularly, the invention is designed for use in buttonhole cutting and stitching machines wherein it is customary to provide punch and anvil cutters for cutting an eyed hole in fabric material while it is held by the work-clamps and prior or subsequent to the formation of the usual overseaming stitches about the hole. When the hole is cut, a small disk of material is clipped from the leather or other fabric material operated upon and it is highly desirable that this cut-out piece of material be immediately removed from the field of operations.

In prior machines of the present type the cutting edge of the punch, after a time, becomes somewhat rounded and smooth at the entrance to the usual punch-passageway and, as a result, the punch fails to cut the work clean even under excessive pressure and also fails to pick up the cut-out piece of material. Moreover, an increase of punching pressure causes the punch to rapidly wear or form a groove in the anvil, thereby impairing its effectiveness since the punch tends to mash the last fibers to be cut into the groove of the anvil without severing them. Consequently, when the punch is elevated, the cut-out piece hangs to the body of the work by a few mashed fibers. When such a cutter is used in connection with an automatically operated train of mechanism effecting the cutting and stitching of the button hole, this failure is a source of great annoyance as the cut-out portion will be sewn into the button-hole, resulting in imperfect work. Further, the cut-out portion will often cause deflection or breakage of the stitching needle or needles.

In the machine disclosed in my Patent No. 473,564, of April 26, 1892, use is made of an upwardly spring-pressed and auto-

matically controlled ejector-pin for shooting the cut-out portion of material upwardly through the punch-passageway. This mechanism, however, is relatively complicated and costly to manufacture and is entirely unsuitable for embodiment in cutter-mechanism which is adapted to travel toward and from buttonhole cutting position.

The primary object of the present invention is to provide a punch-and-anvil cutting device of simplified construction which will cut the work clean under a moderate pressure, pick up the cut-out disks of material with certainty after long continued use, and operate repeatedly over long periods of time without attention on the part of the operator.

A further object of the invention is to provide a punch-and-anvil cutting mechanism which will cut a hole in sheet material and pick up the cut-out piece without recourse to a complication of movable parts additional to the punch and anvil elements.

Still further, the invention has for an object to provide a work-holding and punching mechanism including punch and anvil cutters which will cut a clean hole in the work with an application of less cutting pressure than has heretofore been found necessary, thereby materially lessening the tendency of the cutter element to form the objectionable groove in the anvil element and consequently lengthening the life of said elements.

To these ends the anvil element is provided, within the area defined by the eye of the cutter element, with a hump or protuberance preferably constituted by the rounded head of a small lifter-plug, the reduced shank of which is forced into a hole drilled in the center of the eye-portion of the cutting block or anvil. It has been found by experiment, that this hump or protuberance on the anvil causes the punch to invariably cut and pick up the clipping even when dulled through long continued use. This certainty of operation is probably due to the arching of the material into the mouth of the punch, causing the edges of the cut-out portion to tightly grip the sides of the punch passageway. It is also probable that the hump or protuberance of the present device, in shoving the column of clippings along the passageway, 110

as the cutter descends, relieves the reactionary pressure of the clippings which heretofore contributed to the failure of the punch to pick up the newly formed clipping. 5 Moreover, the hump or protuberance tends, during the cutting action, to strain the fibers of the material against the edge of the cutter, thereby combining a sort of tearing action against the cutting edge with the 10 cutting action caused by direct pressure of the cutter upon the anvil element.

When combined with means for clamping the work at the sides of the position where the hole is to be cut, this hump or protuberance on the anvil element is particularly effective in reducing the pressure required to make a clean cut. When so combined, the work-clamps resist the strain imposed upon the work by the hump as it arches the work 15 into the mouth of the cutter, thereby causing such hump to tension the work within the clamps prior to and during the cutting action. This arching of the cut-out material renders the area of the punching, when 20 subsequently disengaged from the hump or protuberance and in flattened condition, slightly greater than that of the discharge passage in the punch, to which its edges thus cling in the separation of the cutting elements so as to remain lodged therein for retraction from the body-material. Any tendency of the cut-out piece to hang to the body 25 of the work by a few mashed fibers is practically eliminated since the tendency of the strain imposed upon the fibers by the hump is to break or pull apart these fibers which are mashed or otherwise weakened by the 30 cutter.

In the accompanying drawings, Figure 1 40 is a horizontal section through the standard of a buttonhole sewing machine embodying the invention, showing the work-holding and buttonhole cutting mechanisms in plan. Fig. 2 is a side elevation of the parts shown 45 in Fig. 1. Fig. 3 is a side elevation of the punch-and-anvil cutting device used in the above machine. Fig. 4 is a transverse vertical section through the punch and anvil elements in closed position. Figs. 5 and 6 are 50 detail perspective views of the punch-and-anvil elements, respectively.

As illustrated, the invention is embodied in cutting or punching mechanism of the type described in my United States Patent 55 No. 1,048,786 of Dec. 31, 1912, and commonly used in connection with buttonhole sewing machines for cutting the buttonhole in the work. Buttonhole cutting mechanism of this type commonly comprises upper and 60 lower cutter-levers 1 and 2, respectively, fulcrumed at 3 upon the traveling fulcrum-block 3' which, in practice, is shifted longitudinally of the bed of the machine to carry the cutters toward and from cutting position. The upper cutter-lever 1 carries the

usual die or punch element 4 having, in the present instance, a sharpened straight edge-portion 5 joining the sharpened edge-portion 6 which clips out the eye of the button-hole. Leading upwardly from the eye-punching portion 6 is a passageway or channel 7 for the clippings. As shown in Fig. 4, the walls at the lower end portion of the passageway up to the point 8 are substantially perpendicular to the plane of the cutting edge 6. Above the point 8 the walls of the passageway are slightly flared outwardly to permit free upward movement of the column 9 of clippings or punchings. The punch element 4 may be suitably dove-tailed into a 75 block 10 mounted on the lever 1 and held in said block by a set-screw 11.

The cutter-block or anvil 12 comprises a preferably flat surface 13 against which the cutter element 4 acts and is formed with a 80 shank 14 which is fixed within a socket 15 in the lower cutter-lever 2 by a set-screw 16, the end of which bears against the flat surface-portion 17 of said shank.

The hump or protuberance referred to 90 may be made integral with the anvil but is preferably constructed as follows:—Drilled into the eye-portion of the anvil 13 is a small hole 18 into which is forced the shank of a 95 plug 19 having a rounded head 20 fixedly located within the eye-cutting portion and above the plane surface 13 of the anvil.

When the cutting elements 4 and 12 are closed upon the work, the hump 20 arches the material into the mouth of the punch-passageway 7 and tends to shove the column 9 of clippings along the passageway. This arching of the material before it is cut results in the cutting out of a disk of material 10 slightly larger than the hole in the punch, which disk of material on account of its arched position will tend to grip the walls of the passageway and resist downward displacement.

It will be seen that the present device 11 entirely obviates the use of movable plunger or ejector mechanism such as disclosed in my earlier patent above referred to and is consequently cheap to manufacture and free from ill effects of wear and tear. Moreover 11 the present device is readily carried by the usual cutter-levers and may be moved with the latter toward and from cutting position.

After punching mechanism of the present type has been in use for a long time the cutting element 4 wears a groove in the surface of the anvil or cutter-block 12 and, to secure a clean cut, it eventually becomes necessary to dress or file down the surface 13 of the anvil to obliterate the groove. When this 12 operation is performed the plug 19 may be readily driven from its seat and replaced in operative position as soon as the block 12 has been resurfaced.

A punch-and-anvil cutter of the class 13

described, the anvil element of which is formed with a fixed hump within the area defined by the eye of the cutter-element, is particularly efficient when used in combination with means for clamping the work and holding it firmly clamped while it is being cut, so that the material will be tensioned or placed under strain as the hump arches the material into the mouth of the cutter. Referring to Figs. 1 and 2, which illustrate the invention as embodied in a buttonhole sewing machine constructed substantially in accordance with the disclosure of my copending application Serial No. 41,884, filed July 26, 1915, 21 represents a portion of the hollow base from which rises the standard 22 carrying the usual bracket-arm (not shown). Mounted upon the base 1 is the work-holder, common to machines of this type and comprising laterally separable lower clamp-plates 23 upon which are mounted the fulcrum-blocks 24 for the clamping arms 25 carrying at their forward ends the pivoted clamping feet 26 adapted to grip the work against the clamp-plates 23 and cut away at 27 to expose the eyelet-end of a buttonhole. Mounted in the fulcrum-blocks 24 are the substantially aligned rock-shafts 28 connected together at their inner ends by the usual offset pin-and-fork device 29 and carrying cam-projections, such as shown at 30, Fig. 2, adapted to depress the wear-plates 31 sustained by the clamp-arms 25 and close the clamping feet 26 upon the work.

Fixed to one of the rock-shafts 28 is a rearwardly extending arm 32 over which is disposed the front end of the clamp-closing lever 33 fulcrumed at 34 to the bracket 35 fixed to the bed 21. The rear end of the lever 33 is acted upon by the usual clamp-closing cam 36 carried by the cutter-shaft 37 which is journaled within and transversely of the standard 2 and is actuated through the usual one-revolution clutch device 38 from the constantly-running pulley 39. The rock-shaft 28 which carries the arm 32 also has fixed thereto a manually operable arm 40 by means of which the clamps may be closed, when desired, independently of the clamp-closing lever 33. Springs, such as shown at 41, elevate the clamping feet when the shafts 28 are rocked to open the clamps.

The rearwardly directed arms of the cutter-levers 1 and 2 extend respectively, above and below the cutter-shaft 37 and are drawn into engagement with the usual cutter-closing cams 42 and 43 on the cutter-shaft by means of the tension-spring 44 connected at its opposite ends to pins 45 and 46 projecting laterally from the cutter-levers 1 and 2, respectively.

The traveling fulcrum-block 3' carrying the fulcrum-pin 3 for the cutter-levers is

slidably mounted in the usual manner upon the bed 1 and is connected by a link 47 with the usual cutter-advancing and retracting cam 48 fixed to the cutter-shaft. As shown in Fig. 1, the cutters occupy a retracted position during the stitching of the buttonhole. In the present instance, when the cutter-shaft is caused to execute its single rotation during the buttonhole-producing cycle, the cam 36 acts to close the clamps upon the work 75 and the cam 48 advances the cutters to cutting position wherein they are thereupon closed upon the work between the clamping feet 26 by the action of the cams 42 and 43. After the buttonhole is cut the cam 48 withdraws the cutters to ineffective position. 80

The machine is also preferably equipped with mechanism for spreading or separating the clamp-plates either before or after the buttonhole is cut. Such mechanism is preferably constructed substantially in accordance with the disclosure of my copending application Serial No. 180,737, filed July 16, 1917, but may take any of the usual forms. 85

Referring to Fig. 4, it will be readily appreciated that if the work is gripped between the clamping elements 23 and 26 it will be tensioned during the descent of the cutter element 4 when the hump 20 arches the material into the mouth of the channel 95 7. The fibers of the material will therefore be under strain transversely of the direction of movement of the cutter element while the latter is acting. It is no doubt largely due to this condition that the present cutting 100 mechanism produces a clean cut hole in the material with an application of much less pressure than has heretofore been found necessary.

From the foregoing description it will be 105 obvious that the present improvement is particularly adapted to all operations involving the removal of sections of material preparatory to stitching or otherwise reinforcing the edges of the same, whether of 110 keyhole shape, as in the usual form of eyelet-end buttonhole, or of circular or other hollow form as in the case of stitched or otherwise reinforced eyelets.

Having thus set forth the nature of the 115 invention, what I claim herein is:—

1. A cutting device comprising an eyed cutting element having a passageway for the clippings, and an anvil having a surface against which the cutting element is adapted 120 to act to cut a hole in the material, said anvil having a hump in fixed relation therewith and rising from the surface portion thereof within the area embraced by the eye of the cutting element when said eye 125 is in contact with the anvil.

2. A cutting device comprising an eyed cutting element having a passageway for the clippings and an anvil having a surface against which the cutting element is adapted 130

to act to cut a hole in the material, said anvil having a rounded hump in fixed relation therewith and rising from the surface portion thereof within the area embraced by 5 the eye of the cutting element when said eye is in contact with the anvil.

3. A cutting device comprising an eyed cutting element having a passageway for the clippings, an anvil having a surface 10 against which the cutting element is adapted to act to cut a hole in the material, said anvil having a recess within the surface portion thereof embraced by the eye of the cutting element when said eye is in contact with 15 the anvil, and a lifter-plug fixedly secured within said recess.

4. A cutting device comprising an eyed cutting element having a passageway for the clippings, an anvil having a surface against 20 which the cutting element is adapted to act to cut a hole in the material, said anvil having a recess within the surface portion thereof embraced by the eye of the cutting element when said eye is in contact with 25 the anvil, and a lifter-plug driven into said recess.

5. A cutting device comprising a cutting element having an eyed knife-edge and a passageway for the clippings, an anvil having a surface against which the knife-edge is adapted to act to cut a hole in the material, and means for arching the material into the passageway of the cutting element before 30 the cutting action is completed.

35 6. A cutting device comprising an eyed cutting element, an anvil having a surface against which the cutting element is adapted to act to cut a hole in the material, said anvil having a hump rising from the surface 40 portion thereof within the area embraced by the eye of the cutting element when said eye is in contact with the anvil, and work-

holding means with which said hump cooperates to tension the work while it is being cut.

45

7. A cutting device comprising an eyed cutting element, an anvil having a surface against which the cutting element is adapted to act to cut a hole in the material, said anvil having a hump rising from the surface portion thereof within the area embraced by the eye of the cutting element when said eye is in contact with the anvil, and coacting work-gripping devices with which said hump cooperates to stretch the 50 work before and while it is being cut.

55

8. Work-holding and cutting mechanism comprising work-clamping elements, a shaft for closing said elements upon the work, cutting means including coacting cutter and 60 anvil elements for cutting a hole in the clamped work, and operative connections between said shaft and cutting means, said anvil element being provided with a hump for arching the material into the mouth 65 of the cutting element during the cutting action.

65

9. Work-holding and cutting mechanism comprising, in combination, coacting work-clamping elements, coacting punch-and-70 anvil cutting elements occupying an inoperative position remote from the clamping elements, means for relatively moving the cutting and work-clamping elements into cutting relation and means for closing the 75 cutting elements upon the work, said anvil element being provided with a hump for arching the material into the mouth of the punch element as the cutting elements are closed upon the work.

80

In testimony whereof I have signed my name to this specification.

EDWARD B. ALLEN
